ABSTRACT: A device for the transport of bottles comprising two racks facing each other, lining the opposed faces of a parallelepipedic case and having cutouts or notches the shape of which corresponds to that of the neck and bottom of a bottle, respectively. The notches are so disposed in the racks that a bottle is securely maintained in position when its neck and its bottom fit into two facing and associated notches.

FIG.13

FIG.12

FIG.11

DEVICE FOR THE TRANSPORT OF BOTTLES

The invention relates to a device adapted to facilitate the transport of bottles.

Up to now, bottles are usually transported in cases or bins comprising a parallelepipedic case body with internal subdivisions limiting compartments in which bottles, placed in vertical position, rest with their bottom on the bottom of the case.

In these cases or bins, the bottles are not effectively maintained unless the bin or the case is in its normal position, that is with its bottom horizontal.

The device according to the invention allows, on the contrary, the transport of bottles without risk of breaking and this in any position. The bottles are efficiently maintained with respect to accelerations or shocks whatever the direction thereof. An arrangement of same in plastic leads to simple and economical manufacturing.

The device according to the invention comprises two racks, facing each other, to hold the bottles, usually with their axis horizontal when the package is in its normal position, maintaining each bottle by the end of its neck and its bottom by means of housings or cutouts, the arrangements being such that after its introduction, which can eventually be sidewise, a bottle is maintained securely with respect to a displacement in any direction.

The invention contemplates an embodiment in which the cutouts or housings are made in plates which are placed on the walls of a conventional case.

The present invention may be well understood by the following description of several types of embodiments taken as examples.

BRIEF DESCRIPTION OF THE DRAWINGS

FIG. 1 is a diagrammatic perspective view of a case according to the invention;

FIG. 2 is a front view of an element of a device according to the invention;

FIG. 3 is a front view of another element;

FIG. 4 is a cross section showing one step of the introduction of a bottle;

FIG. 5 is a view analogous to FIG. 4 but of another step in the introduction of a bottle;

FIG. 6 is also a view analogous to FIGS. 4 and 5 but still of another step of the introduction;

FIG. 7 is a front view of a device according to a further embodiment of the invention;

FIG. 8 is a section along line 8-8 of FIG. 7;

FIG. 9 is a section along line 9-9 of FIG. 7;

FIG. 10 is a perspective view of a part of a case fitted with a device according to the invention;

FIG. 11 is a front view of a plate according to the invention;

FIG. 12 is a section along line 12-12 of FIG. 11;

FIG. 13 is a section along line 13-13 of FIG. 11.

DESCRIPTION OF THE PREFERRED EMBODIMENTS

Reference is first made to FIGS. 1 to 6. A bottle case according to the invention comprises, in the type of embodiment described, a parallelepipedic case body 10, with walls 11, 12, 13, 14 which can be either solid or provided with holes and a bottom 15. The body 10 can be made either from wood or plastic. The small opposite faces 12 and 14 have the usual recess 16 and 17 for the handling of the case.

According to the invention, the walls 11 and 13 are provided with a rack on their internal faces, respectively 18 and 19, including means to hold bottles in a horizontal position.

Rack 18 can be made of a wooden or plastic plate 20. In a modification when body 20 is made of plastic, it can be obtained directly by molding of the wall.

Rack 18 (FIG. 2) has a lower row of circular cuttings 21 having a diameter slightly larger than the diameter of the body of the bottles which have to be transported. Above each cutout 21, the rack has a slot 22, symmetrical with respect to the vertical diameter 23 of the cutout 21, and which has a semicircular bottom 24, two parallel sides 25 and 26, which are con-

nected to the upper edge 27 of the plate 20 through the corner fillets 28 and 29, the distance between the sides 25 and 26 being slightly greater than diameter of the extreme end of a bottle neck.

5 Rack 19 is also made up from a wooden or plastic plate 30 (FIG. 3). In a modification, rack 19 can be obtained directly from molding the wall 11 in plastic, or with the whole case body. Rack 19 presents, symmetrically with respect to the vertical plane 31, at the same distance from edge 32 as is the vertical plane 23 from edge 33, a wide cutout 34 opening by rectilinear sides 35 and 36 on the upper horizontal edge 37 of plate 30 and having two arcs 38 and 39 which do not join each other but extend through vertical parallel sides 40 and 41 which are spaced by a semicircumference 42, the diameter of which is slightly greater than the diameter of the end of a bottle neck and forms a narrow cutout 43.

Plate 20 has a certain number of pairs of cutouts 21-22, five for example, and plate 30 has the same number of opposite cutouts 34 and 43.

20 Plates 20 and 30 are fastened in the body 10 by any appropriate means: glueing, nailing, tacking, etc.

To fill the case with bottles, one takes a first bottle and introduces it into the case, in a nearly horizontal position but at some obliquity, the neck being maintained higher than the bottom of the bottle so that this bottom can be introduced by its upper part in a lower circular cutout 21, the neck having not yet penetrated completely in the case body as shown on FIG. 4. The bottle is then pivoted in the way shown by the arrow f, the bottom of the bottle being supported by the wall 13, the neck passing through cutout 34 and coming to rest in the narrow cutout 43, the entire bottom penetrating progressively in cutout 21 as shown on FIG. 5. At the end of its motion, the bottle is horizontal as shown on the lower part of FIG. 6; it lies on the lower part 44 of cutout 31 by its bottom end and on arc 42 of cutout 43 by the end of its neck.

35 To place a bottle above the one which has just been housed, said bottle is presented in a horizontal position, such as that shown on the upper part of FIG. 6. The distance between the internal surfaces of walls 13 and 11 is sufficient for the introduction of the bottle in the case; the bottom of the bottle goes by the sides 35 and 36 of the wide cutout 34 and comes to rest on the circular parts 38 and 39 of said cutout. The neck of the bottle finds a housing in slot 22 and it rests by its end on the semicircular bottom 24 of this slot. This position is shown schematically for a half-bottle in the middle part of FIG. 6.

40 All the bottles of the lower and the upper rows are deposited into place as explained.

During transport, a lower bottle is maintained with respect 50 to accelerations in the direction of its axis by the walls 13 and 11 of the case and with respect to accelerations transverse to its axis, i.e. to said walls, by the thrust of its bottom against cutout 21 and by its neck against the sides 40 and 41. The intervals existing between the bottom of the bottle and the opposite case wall are small enough so that there cannot be any danger 55 that the bottle might escape from the housing in the rack in case of accelerations directed lengthwise to the bottle. The bottle is maintained with respect to upwards accelerations by abutment against the bottle of the upper row.

60 With respect to horizontal accelerations, whatever the direction thereof, a bottle in the upper row is maintained in the same way as one in the lower row. With respect to upwards accelerations, the bottle in the upper row is maintained either by a cover placed on the case, or usually by the bottom of another case, similar or identical to the case that has just been described, allowing a stacking of cases just as readily as for ordinary cases.

65 It is also very simple to take out bottles from the case: a bottle of an upper row is extracted by raising it, holding it suitably horizontal by its neck, its bottom or both of them at the same time. The bottle of the lower row, which is thus freed, is taken out by a reverse movement to the one which was used to put it in place, such as explained with reference to FIGS. 4 and 5.

70 The case (or bin) according to the invention has a desirable presentation. Handling of bottles is made easier and faster.

It allows storage in less floor space and with a better stability.

It suppresses completely the risk of ripping the labels which are usually glued on the bottles.

The horizontal position of the bottles is favorable to the demeanor of the liquid which they contain.

The case or bin can be used for a long time without any damage.

Reference is now made to FIGS. 7 to 10. The device according to the invention includes, in this embodiment, a plate 50 which has in its thickness a certain number of housings or cells, which allow, in conjunction with an opposite plate, the support of bottles in a horizontal position. Plate 50 thus comprises, opening on its upper edge 51, a cutout 52, not as deep as the plate, thus leaving a bottom 53, and limited by two sides 54 and 55 slightly convergent and joining along a circular bearing face 56, which has a diameter slightly larger than the diameter of the bottle neck. In the embodiment described, plate 50, which has a rectangular overall form, presents two cutouts 52, references 52₁ and 52₂.

Between cutout 52₁ and the adjacent vertical edge 57 of the plate, there is a housing 58 which includes a circular part 59, the diameter of which is approximately equal to the body of a bottle and which opens through its upper part into a cutout 60, similar to cutout 52 and which ends consequently by a circular part 61.

In the embodiment described, the plate has two such housings, or large housings 58₁ and 58₂. The second one being included between cutout 52₁ and cutout 52₂.

The centers 62₁ and 62₂ of the circular parts 56₁ and 56₂ of the cutouts 52 and the centers 63₁ and 63₂ of circular parts 59₁ and 59₂ of housings 58₁ and 58₂ are aligned on a straight line 64 parallel to the upper edge 51.

Two other large housings 65₁ and 65₂ are also provided in plate 50 the first one between the cutouts 60₁ and 60₂, the second one between cutout 60₂ and edge 66 opposite to face 57. The large housings 65₁ and 65₂ are composed of a circular part, respectively 67₁ and 67₂, and a cutout 68₁ and 68₂, the latter two having circular parts 69₁ and 69₂.

The plate is further provided with two circular housings 70₁ and 70₂ the centers of which are aligned on the straight line 72 joining centers 73₁ and 73₂ of the circular supports 69₁ and 69₂; the housing 70₁ being placed between cutouts 68₁ and the vertical edge 57, and the housing 70₂ being placed between cutouts 68₂ and 68₁.

A device such as the one just described is designed to be placed in a parallelepipedic case or box, made of wood, cardboard or a similar material, along one of its lateral face, in conjunction with an identical plate placed on the opposite lateral face, said second plate being placed, in the box or case, in an inverse position to that of the first plate.

Such an arrangement is shown schematically on FIG. 10, which shows a first plate 82 placed against face 83 of a case or box 80 and a second plate 82' placed against the opposite face 83'. The arrangement is such that the large housing 58₁ of plate 82 is facing the small housing 52₂' of plate 82', the cutout 52₁ of plate 82 facing a large housing 58₂' of plate 82', etc.

To fill with bottles a case or a box thus fitted, a first bottle is deposited into the box at an inclination with its bottom turned towards plate 82 until the bottom of said bottle has been introduced in the circular housing 70₁, the neck being higher than the bottom. Said bottle is then pivoted while it is brought back to a horizontal position. On account of its obliquity, the end of the neck slides down the internal face of plate 82' without any difficulty and goes down in the cutout 68₂'. When it reaches the lower part of the cutout, the bottle neck spreads out slightly the edges 84' and 85' of said cutout relying thereto upon the elasticity of the material constituting plate and then reaches the circular seat 69₂' on which it comes to rest. The bottle is thus completely fixed and remains so whatever the direction of the accelerations to which it might be submitted due to shocks or vibrations to which might be submitted the case or box in which the bottle is placed.

A second bottle is then presented in front of the opening of the box, this bottle being inverted with respect to the first one. It is introduced at an inclination, that is to say with its body lower than its neck and the bottom of this second bottle is introduced in the circular housing 65₂' which is placed above the cutout 68₂'. When said bottle is pivoted to bring it back to a horizontal position, the neck goes down the cutout 60₁ and the movement is continued until said neck comes to rest on the circular seat 61₁, the entrance in said seat being obtained after an elastic deflection of the lower ends of the edges 86 and 87 bounding cutout 60₁.

A third bottle is introduced in the box, head to tail with respect to the second one and its bottom is introduced in the circular opening 59₁; the neck slides down the cutout 52₂' until it comes to rest on the circular seat 56₂'.

The box is thus filled with a first vertical row of three bottles.

A second vertical row of three bottles is then arranged, adjacent to the first row and the bottles are introduced in a way similar to the one described above, then a third row, so that after completion of the filling the box contains twelve bottles.

Each bottle is horizontal; it is maintained with respect to any movement, in whatever direction, by abutment on bottoms 53 and 53' for accelerations directed parallel to the axis of the bottles, and by the seats or cutouts for transversal accelerations. The strength of the box is increased considerably by the introduction of the plates as well as by the bottles themselves which are used as stiffeners.

The plates, advantageously made of plastic such as polyester or similar material, play a thermal insulation role. The device can be designed for the transport of a number of bottles different from the one allowed by the embodiment described.

The number of housings in a plate can be different from the one in this embodiment.

It is possible to several plates in the same box, either side-by-side side or superposed.

Reference is now made to FIGS. 11 to 13, relating to still another form of embodiment.

The plate which is advantageously made of expanded polystyrene, or a similar material, has three types of cavities in its thickness. A large cavity 100 which is made of a seat or cylindrical housing 101, prevailing over a large part of the circumference, which is prolonged by a notch or cutout 102 limited by two oblique faces 103 and 104 that open into a small circular housing 105, designed to receive the neck of a bottle. The foreface 106 of notch 102 is oblique so as to form a step or shoulder 107 at its connection with the small housing 105. The upper part of the large housing 101 opens outward the rear face 108 of the plate thus presenting a semicircular opening, which is limited by a semicircumference 109. The entrance of the large housing 101 has advantageously a chamfer 110.

A middle-sized cavity 111 placed under the large housing 100 provides a circular housing bounded in its upper half (on FIG. 11) by a chamfered face 110', the upper half-housing opening outwards. The internal face 112 of the lower half is parallel to the external face 108.

A small cavity 113 placed near a large cavity 100 forms a housing for a bottle neck. It is made by a notch 102, similar to the one previously described, and a small circular housing 105 with a shoulder 107.

The introduction and the arrangement of the bottles are made in a way similar to the one described with reference to FIGS. 7 to 10. The cut 109 allows the bottom of the bottle, when the latter is presented slantwise, to go beyond, by a part of its circumference, the external face 108, thus allowing the neck of said bottle to go down along the slanted face 106 of the small opposed housing 113; thus when the bottom of the bottle rests on the lower part of the circular shoulder 101, the bottle neck is locked with respect to an upward movement by abutment on shoulder 107. The arrangement ensures the immobility of the bottle even if the case is put down on the face

opposite to the one that was the lower face when the bottles were put in. The immobility with respect to a longitudinal movement is obtained by abutment against the semicircular bottom 114 of cavity 100 and against the bottom 115 of cavity 113.

A bottle is put in a cavity 111 and an opposite cavity 113 in a similar way and it is maintained with the same efficiency.

I claim:

1. A casing adapted for holding a plurality of bottles in a horizontal attitude, each of said bottles having a neck portion and a bottom portion of greater cross section than that of the neck portion thereof, said casing comprising a pair of opposed walls each provided with a plurality of cooperatively opposing recesses, each of said cooperatively opposing recesses being constituted of a first portion and a second portion, said first portion being of sufficient width for accommodating said bottom portion of one of said bottles, said second portion being of smaller width than that of said first portion and of sufficient width for accommodating said neck portion of another of said bottles, said recesses being arranged in said walls such that said first and second portions of respective recesses in one wall open into one another for communication with one another and further such that each said first portion in one wall is respectively concentric with each said second portion in the other wall, whereby said cooperatively opposing recesses coact with one another for supporting said bottles in a horizontal attitude.

2. A casing as claimed in claim 1 wherein said pair of opposed walls are plates removably supported in said casing.

3. A casing as claimed in claim 2 wherein said recesses are further constituted by an intermediary portion interposed between said first and second portions, said intermediary portion varying in depth and extending at a maximum depth from said first portion to a minimum depth at said second portion, said first and second portions being substantially of equal depth, said maximum depth of said intermediary portion being substantially equal in depth to said first and second portions.

4. A casing as claimed in claim 3 wherein said first and second portions are substantially circular, and said intermediary portion is substantially rectangular.

5. A casing as claimed in claim 1 wherein at least one of said pair of walls is resilient.

6. A casing as claimed in claim 5 wherein the resilient wall is constituted of expanded polystyrene.

7. A casing as claimed in claim 1 wherein said recesses are arranged in horizontal rows in each of said walls such that each of said first portions in one row is separated horizontally from each of the other first portions in said one row by respective second portions interposed adjacent theretwixen.

8. A casing as claimed in claim 7 wherein the adjacent first and second portions in each horizontal row have centers commonly disposed in a horizontal row.
